UNITED STATES PATENT OFFICE.

THADDEUS F. MACEOY, OF NEWARK, NEW JERSEY.

WALL-FIXTURE.

1,086,829.

Specification of Letters Patent.

Patented Feb. 10, 1914.

Application filed April 9, 1913. Serial No. 760,022.

To all whom it may concern:

Be it known that I, THADDEUS F. MACEOY, citizen of the United States of America, and a resident of Newark, county 5 of Essex, and State of New Jersey, have invented certain new and useful Improvements in Wall-Fixtures, of which the following is a specification.

My invention relates to improvements in 10 wall fixtures and the like, such for example as soap dishes, towel holders, tumbler holders, etc., and comprises a fixture of the class described having improved fastening means, whereby the detachment of the fixture is 15 made practically impossible without the use of violence, once the fixture has been put in place.

My invention consists in the novel fastening means for wall fixtures and the like, 20 hereinafter described, and set forth in the appended claims.

The object of my invention is to provide 25 an improved and simple fastening for wall fixtures, etc., which shall make very difficult the removal of the fixture, once it has been put in place.

I will now proceed to describe my invention with reference to the accompanying 30 drawings, and will then point out the novel features in claims.

Figure 1 shows a side elevation and partial section of one form of wall bracket embodying my invention, the sectional portion of the figure showing the fastening means 35 employed. Fig. 2 shows a face view of the base plate of such bracket. Fig. 2^a shows a longitudinal section of the structure shown in Fig. 1, and shows the key hole adapted to receive the expanding key. Fig. 3 shows a rear view of that base plate. Fig. 4 shows a central vertical section of another 40 form of wall fixture provided with fastening means embodying my invention. Fig. 4^a shows a longitudinal section of a portion 45 of the structure shown in Fig. 4, and shows the key hole adapted to receive the expanding key. Fig. 5 shows a front view of the wall fixture shown in Fig. 4. Fig. 6 shows a central section of a portion of the base 50 plate of a wall fixture and of an expansion sleeve which may be employed when the fixture is to be applied to a tile or cement or stone surface or the like: Fig. 7 shows a side view of the expansion sleeve, and Fig. 8 a rear end view thereof. Fig. 9 shows a 55 side view of the head of one form of screw

which may be employed as the expanding key. Fig. 10 is a fragmentary detail section illustrating an alternative construction.

Referring first to Figs. 1, 2 and 3, numeral 1 designates the base plate of the wall fixture there shown, said base plate having a central screw threaded recess 2, at the bottom of which is a hole 3 through which a suitable fastening screw 4 may be passed for 60 the purpose of securing the base plate to a wall, partition, etc.; the head of the screw lying within the recess 2. The said base plate is provided further, to one side of the hole 3, with an eccentric spur 5 which fits 65 into a suitable hole in the wall or partition, thereby preventing the base plate from being turned once it has been applied.

6 designates a supporting member (a post or bracket in the construction shown) 70 provided with a screw threaded boss screwing into the screw threaded recess 2, and which, when so connected to the base plate 1, covers the head of the screw 4, thus entirely concealing the means by which the base plate 75 is secured to the wall or partition or the like. To prevent the post or bracket 6 from being unscrewed once it has been put in place, a diagonal hole 7 (Fig. 2^a) is provided which hole passes through both the 80 base plate 1 and the end of the post or bracket 6, and is of inwardly flaring contour; and after the base plate 1 has been secured in place, and the post 6 has been screwed home in the recess 2 of said base 85 plate, a split expanding key 8 is placed in this hole 7. In the construction shown in Fig. 1 this key has the form of a screw; but in the construction shown in Fig. 4 hereinafter described, the key, there designated 90 by numeral 8^a, has the form of a split expanding pin. Either construction of key may be used, as preferred. If a screw is employed as the key, the key slot in the end of such screw is preferably shallow, so 95 that, once screwed home, it is practicably impossible to remove such screw by means of an ordinary screw driver; or, as illustrated in Fig. 9, the screw, there designated by numeral 8^b, may have a head of such 100 form that special means is required for turning it. In the construction shown in Fig. 9 the head of the screw is provided with two very small recesses 9 which may be engaged only by a special driver having 105 projecting pins corresponding to such holes.

The device shown in Figs. 4 and 5 is simi-

lar to that shown in Figs. 1 and 2, differing principally in form and proportions of the parts. It comprises a base plate 1^a, a face plate or supporting member 6^a having a central boss 6^b adapted to screw into the recess 2 of said base plate 1^a, said base plate having a spur 5^a adapted to fit into a corresponding recess formed in the wall or partition to which the base plate 1^a is being applied. As in the construction shown in Fig. 1, a screw 4 is provided for holding the base plate in place. A suitable flaring hole 7^a (see Fig. 4^a) is provided at the edge of the combined device 1^a—6^a, this hole lying partly in the base plate 1^a and partly in the face plate 6^a; and into this hole a suitable expanding pin 8^a is fitted after the base plate 1^a has been secured in place, and after the face plate 6^a has been secured thereto. When my improved wall fitting is to be applied to a tile, cement, brick, or stone wall or partition, and therefore when the use of an ordinary wood screw for securing the base plate is not practicable by itself, I provide in such wall or partition a recess of sufficient size to receive an expansion sleeve 10, shown more clearly in Figs. 7 and 8. These expansion sleeves are well known. The expansion sleeve having been set in place, the base plate 1^a is applied and the screw 4 is screwed into the expansion sleeve 10, so expanding the same, as indicated in Fig. 6. It being practically impossible to pull such an expansion sleeve out of the socket in which it is fitted, once that sleeve has been expanded, and the head of the screw 4 being concealed once the parts of the wall fixture have been assembled, it then becomes substantially impossible to remove the wall fixture, even when secured to a tile, cement, brick or stone surface. Various devices may be supported by the bracket 6, or face plate 6^a. In Fig. 1 I have indicated in dotted lines one device 11 which may be supported by the post or bracket 6, and in Fig. 4 I have indicated a portion of a wire basket or the like 12 which may be supported by the face plate 6^a. It is obvious that the particular device supported by the wall fixture is immaterial. It will also be obvious that the wall fixtures shown are clearly adapted to be secured to a floor or ceiling; therefore I do not wish it to be understood that, in terming my device a wall fixture, I am limiting my invention to fixtures intended to be secured to walls only. To the contrary my invention is inclusive of fixtures designed to be secured to floors, ceilings, doors, desks, cabinets, and all other objects to which such fixtures are applicable. But while I prefer to so secure the base and supporting member together that, when once so secured, they may not be separated and may not be removed from the surface to which they had been secured,

except by violence, I may at times dispense with means for so locking the base and supporting member together that they may not thereafter be separated except by violence. In many cases, as for example, when fixtures are to be secured to a tile wall, it is desirable to secure a base to such wall and then to secure the main supporting member to such base; and in such cases it is desirable that the means by which the base is secured to the wall shall be concealed by the supporting member when in place; since wall fixtures so made are neater in appearance than those which disclose to view the means by which the base is secured to the wall. Also, when the means by which the device is secured to the wall or other support is concealed, there is substantial protection against theft, since it is not apparent to the observer how to detach the fixture from the wall. I may therefore omit the expanding key, 8 or 8^a, and omit the hole into which that expanding key is fitted; or I may provide a key hole adapted to receive a plain key as distinguished from an expanding key. Fig. 10 shows a construction wherein a plain key 8^b is provided.

What I claim is:

1. A fixture such as described comprising a base provided with means whereby it may be secured to a suitable object, and a supporting member, said base and supporting member having the one a screw-threaded socket and the other a correspondingly screw-threaded boss, whereby said base and supporting member may be secured together, said supporting member arranged when so connected to the base to cover and prevent access to the fastening means for said base, said base and supporting member provided jointly with a key-opening located partly in said base and partly in said supporting member and adapted to receive a key, whereby when such key has been put in place the disconnection of such base and supporting member is precluded.

2. A fixture such as described comprising a base provided with means whereby it may be secured to a suitable object, and a supporting member, said base and supporting member having the one a screw-threaded socket and the other a correspondingly screw-threaded boss, whereby said base and supporting member may be secured together, said supporting member arranged when so connected to the base to cover and prevent access to the fastening means for said base, said base and supporting member provided jointly with a key-opening located partly in said base and partly in said supporting member and adapted to receive a key, and a key in such key opening, whereby the disconnection of such base and supporting member is precluded.

3. A fixture such as described comprising

a base provided with a screw-threaded socket and with a screw hole at the bottom of such socket adapted to receive a screw by which said base may be secured to a suitable object, 5 and a supporting member having a screw threaded boss adapted to screw into said socket and thereby to cover the head of such screw, said base and supporting member provided jointly with a key-opening located 10 partly in said base and partly in said supporting member and adapted to receive an expanding key whereby, when such expanding key has been put in place the disconnection of such base and supporting member is 15 precluded.

4. A fixture such as described comprising a base provided with a screw-threaded socket and with a screw hole at the bottom of such socket adapted to receive a screw by which 20 said base may be secured to a suitable object, and a supporting member having a screw threaded boss adapted to screw into said socket and thereby to cover the head of such screw, said base and supporting member provided 25 jointly with a key-opening located partly in said base and partly in said supporting member and adapted to receive an expanding key, and an expanding key within such key-opening, whereby disconnection 30 of such base and supporting member is precluded.

5. A fixture such as described comprising a base, provided with means whereby it may be secured to a suitable object, and a supporting member, said base and supporting 35 member having the one a screw-threaded socket and the other a correspondingly screw-threaded boss, whereby said base and supporting member may be secured together, said supporting member arranged when so 40 connected to the base to cover and prevent access to the fastening means for said base.

6. A fixture such as described, comprising a base provided with a screw hole adapted to receive a screw whereby said base may be 45 secured to a suitable object, and a supporting member, said base and supporting member having the one a screw-threaded socket, and the other a correspondingly screw-threaded boss, whereby said base and supporting member may be secured together, 50 said supporting member arranged when so connected to the base to cover and prevent access to a screw located in the said screw hole of said base. 55

In testimony whereof I have signed this specification in the presence of two subscribing witnesses.

THADDEUS F. MacEVOY.
